Primary Examiner — Catheri Oliver-Garcia(74) **Attorney, Agent, or Firm** — Fellers, Snider, Blankenship, Bailey & Tippens, P.C.(57) **CLAIM**

The ornamental design for a baitcast fishing reel, as shown and described.

DESCRIPTION

FIG. 1 is front and left side perspective view of the baitcast fishing reel of the invention;

FIG. 2 is a front elevational view of the reel of FIG. 1.

FIG. 3 is a rear elevational view of the reel of FIG. 1.

FIG. 4 is a left side elevational view of the reel of FIG. 1;

FIG. 5 is a right side elevational view of the reel of FIG. 1;

FIG. 6 is a top plan view of the reel of FIG. 1.

FIG. 7 is a bottom plan view of the reel of FIG. 1; and,

FIG. 8 is a rear and left side perspective view of the reel of FIG. 1.

The dashed lines in the figures are for illustrative purposes and form no part of the claimed invention.
